Primary Examiner — Karen E Eldridge Powers(74) *Attorney, Agent, or Firm* — Nixon & Vanderhye P.C.(57) **CLAIM**

The ornamental design for a cuff for air delivery tube, as shown and described.

DESCRIPTION

FIG. 1 is a front perspective view of a cuff for air delivery tube according to our new ornamental design; FIG. 2 is a front view thereof, with the rear view being identical thereof;

FIG. 3 is a top view thereof, with the bottom view being identical thereto;

FIG. 4 is a left side view thereof; and,

FIG. 5 is a right side view thereof.

The broken lines represent environmental structure of the cuff and do not form a part of the claimed design.
